US00D962327S

(12) **United States Design Patent** (10) Patent No.: **US D962,327 S**
(45) Date of Patent: **** Aug. 30, 2022**

(54) **CAMERA HOLDER**

(71) Applicant: **Yuzhen Zhong**, Ganzhou (CN)

(72) Inventor: **Yuzhen Zhong**, Ganzhou (CN)

(**) Term: **15 Years**

(21) Appl. No.: **29/739,110**

(22) Filed: **Jun. 23, 2020**

(51) LOC (13) Cl. **16-05**

(52) U.S. Cl.
USPC **D16/242**

(58) **Field of Classification Search**

CLAIM

The ornamental design for a camera holder, as shown and described.

DESCRIPTION

FIG. 1 is a front and top perspective view of a camera holder, showing my new design;

FIG. 2 is a rear and bottom perspective view thereof;

FIG. 3 is a rear elevational view thereof;

FIG. 4 is a front elevational view thereof;

FIG. 5 is a left side elevational view thereof;

(Continued)

FIG. 6 is a right side elevational view thereof;
 FIG. 7 is a top plan view thereof; and,
 FIG. 8 is a bottom plan view thereof.
 The broken lines in the figures illustrate portions of the camera holder that form no part of the claimed design.
